BROODER STOVE AND HOVER

Application filed July 10, 1926. Serial No. 121,729.

This invention relates to brooders and particularly to means for heating a brooder and the general object of the invention is to provide a stove for this purpose which is very simple, may be cheaply made, which is thoroughly effective, and which will not overheat the brooder.

A further object is to provide means for automatically controlling the draft through the stove and thereby controlling the heat, this means being in turn controlled by a thermostat and another object is to provide means for this purpose which not only controls the amount of draft passing upward through the fire but controls a check draft damper.

A still further object is to provide a hover adapted to be mounted upon the stove and extend downward and outward therefrom and which is capable of being raised or lowered upon the cylindrical barrel of the stove, this hover being so constructed as to provide a dead air space around the stove at the point of junction with the hover.

Other objects will appear in the course of the following description.

My invention is illustrated in the accompanying drawings wherein:

Figure 1 is a vertical sectional view through my improved brooder stove;

Fig. 2 is a section on the line 2—2 of Figure 1;

Fig. 3 is a section on the line 3—3 of Figure 1;

Fig. 4 is a detailed sectional view showing the connection of the draft damper to the thermostat operated rod;

Fig. 5 is an elevation of the thermostat.

Fig. 6 is an elevation of the check draft damper casing and showing another means whereby the check draft may be operated.

Referring to these drawings 10 designates the ash pit of the stove, 11 the grate, 12 the fire pot, and 13 the fuel magazine. This fuel magazine is cylindrical in form and provided with an opening in its top normally covered by a lid 14 through which coal may be supplied to the magazine. The fire pot extends upward and outward and at its upper end has a greater diameter than the diameter of the magazine and there is formed between the

lower end of the magazine and the upper end of the fire pot an annular smoke chamber 15. The rear half of this smoke chamber is closed at its bottom by an annular wall 16 but the front half of the smoke chamber is open at the bottom to provide a heat expansion chamber above the fire pot. The magazine, the annular smoke chamber, and the fire pot may be formed in any suitable or desired manner and either integral or formed in sections.

Extending upward from the smoke chamber at the rear of the heater is the smoke flue 17 which at a point above the top of the magazine 13, extends into a draft control chamber designated generally 18. This chamber has projecting from it short sections of pipe 19 whereby the chamber may be connected to the lower section 17 of the smoke flue and to an upper section 20. The draft controlled chamber is preferably circular in cross section and is formed on one side with a relatively enlarged opening 21.

Pivoted upon a longitudinally extending pintle 22 is a curved damper plate 23 which, when it swings over in one direction, bears against the wall of the chamber 18 and closes the opening 21. When more heat is desired this damper will swing to its closed position and when less heat is desired the damper will open and the air will pass down through the flue 17 and check the fire. The pintle 22 is provided with a crank 24 whereby the damper 23 may be operated from a thermostat.

Air is admitted into the ash pit by means of a duct 25 which is preferably rectangular in cross section and extends upward and outward from the ash pit at the rear thereof. This duct at its upper end carries a swinging door or damper 26 which is designed to be operated in correspondence with the damper 23.

Mounted upon one side wall of the fresh air duct 25 is a bracket 27 and pivotally mounted upon the outer end of this bracket is a lever 28. The free end of this lever 28 carries a rod 29 which is adjustably engaged with the free end of the lever, this rod extending upward parallel to the flue 17 and being engaged at its upper end with the crank 24. The free edge of the draft door 26 has a bail 30 and

adjustably mounted upon the rod is a sleeve 31 having a hook 32 engaging this bail. This sleeve is adjustable upon the rod 29 by means of a set screw 33.

5 Mounted upon the bracket 27 are the two disk thermostats 34 and 35, each thermostat consisting of two elements and expanded under the action of heat and contracted under a cooling action. Bars 36 connect the two 10 pairs of elements and shift as the elements expand or contract and these bars extend across the bracket 27 and the lever 28. Thus, as the thermostat expands, the lever 28 will be moved away from the bracket 27 and this 15 will act to shift the door 26 toward its closed position and shift the damper 23 towards its open position and vice versa. As a less degree of heat causes the thermostats to contract, the lever will be drawn upward, thus 20 opening the draft door to permit more air to pass to the fire and closing the check draft damper. Preferably the rod 29 extends upward through a tubular guide 33^a carried upon or formed as part of the flue 17. Preferably also the flue 17 is engaged with the upper wall of the smoke passage 15 by means of the upwardly extending flange 34.

Surrounding the magazine 18 and the flue 17 and vertically movable thereon is a metallic collar 35 which in practice will be about 30 4" wide, and attached to the upper edge of this collar and extending downward and outward therefrom is a roof or hover made of light metal designated 36. Attached to the 35 lower edge of the collar 35 is an annular piece of sheet metal designated 37 which extends outward and upward and is attached to the sheet metal 36 a few inches from the collar to thus form a dead air space between 40 the two sheets of metal at the top of the hover.

As the collar is made to fit closely around the magazine, it will prevent all escape of heat at this point and the heat is carried downward and outward beneath the hover 36 toward the outer edge thereof and thus a very even distribution of heat is secured. The hover 36 should extend to within 7" or 8" of 45 the floor.

The type of stove which I have designed 50 and heretofore described, is particularly simple in construction, has been thoroughly efficient and in particular will hold the heat close to the lower part of the stove owing to the construction of the magazine and to the 55 provision of an annular heat chamber between the bottom of the magazine and the upper part of the fire pot. The draft is at all times automatically controlled by means of the thermostat and thus the temperature of 60 the brooder may be kept uniform. The roof or hover 36 may be adjusted upon the magazine to any desired height and thus on cold days it may be brought down close to the chicks, thus preventing any too great loss of 65 heat and on warm days may be elevated.

The hover 36 may be removed entirely from the magazine by simply removing the damper section 18 and the pipe section 20.

While I have heretofore referred to the check draft damper as being operated by the 70 pintle 22 connected, through its crank arm 24, with the operating rod 29, I do not wish to be limited to this and the damper 23, as 75 illustrated in Figure 6, may be provided with an outstanding arm 38 attached to the face of the damper and extending out through the opening 21 so that this arm may be connected to the operating rod 29 instead of connecting the crank 24 to the operating arm. This manner of connection secures a direct 80 pull upon the damper to open and close it and it is to be particularly noted that the casing 85 18 may be shifted so as to bring the opening 21 opposite the operating rod 29 as in Figure 6, or bring this opening 21 to one side as shown in Figure 3, and connect the operating rod 29 to the crank 24.

The damper chamber 18 is preferably disposed about six inches above the top of the magazine in order to permit the hover to be 90 raised clear of the stove and the damper is weighted somewhat so as to overcome the weight of the draw rod and lever on the thermostat and thus cause the damper to be urged to a closed position.

I regard the smoke chamber 15 as being 95 very essential as without this chamber a great deal more of the heat would be carried out of the fire pot into the flue than is the case where the smoke chamber is used. This 100 smoke chamber tends to retard the heat, thus utilizing more of it and distributing the heat more evenly around the fire pot. Furthermore it causes the draft to be more evenly distributed.

The object of making the chamber 18 circular in cross section is to eliminate any 105 square corners which tend to collect soot and which would tend to prevent the even flow of air. Furthermore by making the chamber circular in cross section the damper will 110 close against the margin of the air opening more certainly than it otherwise would.

I claim:

1. A brooder stove of the character described comprising an ash pit, a fire pot extending upward and outward from the ash pit and having a grate at its lower end, a cylindrical magazine extending upward from the top of the fire pot, the lower end of the magazine being less in diameter than the diameter of the fire pot at its top, and an annular smoke chamber extending around the base of the magazine above the fire pot, the smoke chamber having a bottom wall for part of its length, and a flue extending upward from the smoke chamber at a point above the bottom, the wall flue at one point in its length being provided with a check draft opening, a check draft damper disposed 125 130

in the opening, and thermostatic means for controlling this damper.

2. A brooder stove having an ash pit, a fire pot, a cylindrical magazine extending upward from the top of the fire pot, the lower end of the magazine being less in diameter than the bottom of the fire pot at its top, an annular smoke chamber having an outer wall, the outer wall being detachably mounted upon the top of the fire pot and having a diameter the same thereas, the lower end of the magazine being detachably engaged with the top of the inner wall for part of its length and having a flue opening in its top wall at a point above said bottom wall, the magazine carrying a flue extending upward from the flue opening of the smoke chamber and to a point above the magazine, the flue at a point above the magazine being provided with a check draft opening, a check draft damper disposed within the opening, and thermostatic means disposed adjacent the lower portion of the fire pot for automatically controlling the inlet of fresh air to the fire pot and controlling said check draft damper.

3. The combination with a brooder stove having a flue, of a transversely circular check draft damper casing mounted upon the flue for rotative adjustment around a vertical axis and having an opening in one face, a check draft damper hingedly supported at its upper end within the casing for inward swinging movement toward or from said opening and having an arm extending out through said opening and having its hinge pintle extending through the end wall of the casing and having a crank arm thereon exterior to the casing, the brooder stove having an air inlet, a thermostat disposed adjacent the base of the brooder stove, a damper for controlling the inlet of air through the last named opening, and means operated by the thermostat for shifting both of said dampers, one reversely to the other.

4. The combination with a stove having an air inlet in its base and having a flue, of a transverse check draft damper casing mounted upon the flue for rotative adjustment around a vertical axis and having an opening in one face, a curved check draft damper hingedly mounted at its upper end within the casing for inward swinging movement toward or from said opening, the damper when closed approximately fitting the curvature of the wall defining said opening, a thermostat disposed adjacent the base of the stove, a damper for controlling the passage of air through said air inlet, and means operated by the thermostat for shifting both of said dampers, one reversely to the other.

In testimony whereof I hereunto affix my signature.

ROSCO O. PENCE.
